RADIO RECEIVING SYSTEM

David Arthur Bell, London, England, assignor to
 A. C. Cossor Limited, London, England, a British company

Application August 14, 1944, Serial No. 549,459
 In Great Britain September 17, 1943

3 Claims. (Cl. 250—20)

1

This invention relates to apparatus for demodulating an input signal which consists of a succession of identical direct voltage pulses, which signal is angularly modulated (that is to say the frequency or phase of pulse repetition is modulated) in accordance with the intelligence to be conveyed.

The original received input signal, unless it already consists of a succession of identical direct voltage pulses, must be converted into such form. If, for example, it consists of a succession of short trains of radio-frequency oscillation, this conversion may be effected by an ordinary detector, together with a limiter if necessary.

The invention makes use of a known method of effecting demodulation of such an input signal, namely mixing with the input signal consisting of a succession of identical direct voltage pulses a saw-tooth oscillation having the same mean frequency as the signal in order to produce an output component which varies in accordance with the phase relationship of the signal and the saw-tooth oscillation and therefore represents the modulation of the input signal.

The maximum depth of time or phase modulation, that is the maximum deviation of frequency or phase, that can be dealt with by the known method referred to is limited by the fact that it must be arranged that only one of the direct voltage pulses occurs during each cycle of the saw-tooth oscillation. It is known to be desirable to use a relatively high depth of modulation at least over the earlier part of a communication channel in order to obtain a favorable signal to noise ratio and the present invention has for its object to permit the depth of modulation to be increased beyond what is possible with the known method referred to.

For this purpose the invention applies a novel form of negative feedback which while permitting the depth of modulation to be increased also has, in common with known forms of negative feedback, a beneficial effect upon the faithfulness of reproduction of the original modulation. The negative feedback is applied in the present invention to vary the instantaneous frequency or phase of the saw-tooth oscillations in accordance with the instantaneous frequency or phase of the input signal and to nearly but not quite

2

the same extent. The effect of this, as with known forms of negative feedback, is to reduce the amplitude of the output signal, but the reduction in output signal can readily be compensated for by further amplification at modulation frequency.

This modulation frequency component is filtered to free it from components of higher frequency, for example by providing the hexode with a load consisting of a resistor with a by-pass condenser. It is then used to vary the frequency of the saw-tooth oscillation, for example by its application as control bias voltage to a grid of the oscillator valve. At the same time this modulation frequency component serves as the demodulated output signal.

It is essential that the phase displacement between the input signal and the saw-tooth oscillation shall not vary to such a degree that during a cycle of the saw-tooth oscillation either more or less than one pulse shall occur. The frequency-or phase-following by the saw-tooth oscillation may, however, be so close that the modulation may have a depth of many cycles of the mean pulse repetition frequency.

In the accompanying drawing, Figures 1 and 3 are circuit diagrams of receivers for radio signals consisting of a succession of short trains of radio-frequency oscillation, the frequency of repetition of which is modulated. Figures 2a, 2b and 2c are diagrams to illustrate the operation of the receiver shown in Figure 1.

In the receiver shown in Figure 1, the radio signal is picked up by the aerial 22 and selected in the radio-frequency tuned circuit comprising inductance 1 and condenser 2. The voltage developed across this tuned circuit is applied to the input grid 40 of the pentode valve 3, which is arranged to operate as an anode-bend detector. By this means each train of oscillations in the received signal produces a pulse of current to the anode 41 of the valve 3, and these pulses of current in turn are converted into direct voltage pulses by the anode resistance 24. This voltage is applied via the lead 42, D. C. blocking condenser 5 and lead 43 to the mid-point of the secondary winding of transformer 21.

This transformer forms part of a balanced diode circuit which comprises the transformer

27, diodes 25 and 26, diode load resistances 28 and 29, the latter being shunted by condensers 30 and 31; and the output from the balanced diode circuit is delivered to the audio-frequency amplifier 33 through the transformer 32. Two voltages are applied to the balanced diode circuit, the first consisting of the pulses applied through the lead 43 from detector 3, as already described, and the second being a saw-tooth voltage oscillation applied through the primary of the transformer 27.

The saw-tooth oscillation is generated by triode valve 35 which operates in known manner as a blocking oscillator. The frequency of the saw-tooth oscillations is dependent upon the potential applied to the grid 44 through grid leak resistance 38. Current from the anode 46 of the valve 35 flows through coil 47, which couples to the grid coil 48 for the purpose of maintaining oscillations, and through resistor 36 which is shunted by condenser 37. The anode current of the blocking oscillator consists of short pulses, and the time-constant of the network 36, 37, is such that the time of discharge of condenser 37 through resistor 36 is considerably greater than its time of charging through the anode-to-cathode path of triode 35. The pulse output normally produced by the blocking oscillator is thus converted into an oscillation of saw-tooth (but not linear saw-tooth) form. The condenser 37 must, of course, be considerably discharged between successive pulses from the blocking oscillator; the time-constant of the network 36, 37 should therefore be of the order of half the mean pulse-repetition interval. The voltage of approximately saw-tooth wave-form thus generated is applied through the blocking condenser 39 and the leads 49, 50, to the primary coil of transformer 27.

The modulation-frequency component of the resultant of the mixing by the balanced diode circuit of the signal pulses applied through lead 43 and the saw-tooth voltage applied through leads 49, 50, is developed across the anode loads of the diodes, comprising resistors 28, 29, with parallel condensers 30, 31. These condensers are designed to by-pass components having frequencies of the order of the pulse-repetition frequency, so that it is the modulation-frequency component of the resultant which appears as a voltage across the anode loads. The junction of the resistors 28 and 29 is at earth potential (and is connected to the cathode of valve 3 by lead 53) and therefore the modulation-frequency signal is taken through audio-frequency transformer 32 before amplification in amplifier 33 and reproduction in loud speaker 34.

The modulation frequency signal developed across resistors 28 and 29 is also applied through leads 51 and 52 to the cathode 45 and to the end of leak resistance 38 to control the frequency of the blocking oscillator. In this case the direct component of the signal is required to be conserved, and therefore a separate high tension battery B2 is provided to supply this oscillator. The conservation of the direct component is necessary so that the mean frequency of the oscillator shall coincide with the mean repetition frequency of the pulse signal.

The blocking oscillator comprising triode 35 is designed to oscillate at approximately the mean repetition frequency of the pulses in the signal to be received, and its frequency of oscil-

lation is highly dependent on the voltage applied between the cathode of triode 35 and the end of grid leak 38. The modulation frequency component of the voltage developed across resistors 28 and 29, being so applied, is therefore able to control the frequency of the saw-tooth oscillation output which is developed across resistor 36, which is thence applied through D. C. stopping condenser 39 to the primary of transformer 27. The degree of this control is such that the frequency or phase of the saw-tooth oscillation is modulated in accordance with, and to nearly the same depth as, the frequency or phase modulation of the signal developed across resistor 24.

In the circuit of each of the diodes 25 and 26, the saw-tooth voltage injected through transformer 27 and the pulse voltage applied through condenser 5 will be added. The resulting wave-form of voltage applied in the circuit of diode 25 is shown in Figure 2a. The three successive cycles in this figure represent different phases of the direct voltage pulse signal with respect to the saw-tooth voltage. Diode 25 becomes conducting only when its cathode is negative, so the only parts of the resulting wave-form which are effective to produce current through the load 28-30 are those represented by the shaded areas in Figure 2a.

Figure 2b similarly represents the voltages applied in the circuit of diode 26, the pulses in this figure having the same sense as those in Figure 2a, while the saw-tooth has opposite sense.

The curve shown in Figure 2c is obtained by subtracting the shaded area of Figure 2b from the shaded area of Figure 2a. The resultant output voltage from the balanced diode circuit is the modulation-frequency component of the resultant of this subtraction. It will be seen from inspection of this figure that the contribution from the saw-tooth input, over a whole cycle, is equally positive and negative, and therefore averages zero; but the contribution due to the applied pulses may be positive, zero or negative, according to the relative phase of the pulses and the saw-tooth wave.

It will be seen that because of the control of the frequency of oscillation of the blocking oscillator by the modulation-frequency voltage fed thereto through leads 51 and 52, the depth of modulation of the signal received by the circuit of Figure 1, that is to say the frequency or phase deviation of the direct voltage pulses, may be made much greater than would be possible in the absence of such control of frequency, having regard to the fact that only one pulse must be allowed to occur during each cycle of the saw-tooth oscillation. The overall signal to noise ratio can, therefore, be increased as compared with systems in which no such frequency control is provided. In addition the control behaves much in the same way as the well-known forms of negative feedback in amplifier circuits and leads to an improvement in the faithfulness of reproduction of the original modulation.

The multiplicative nature of the circuit will also be seen by consideration of Figure 2c. It will be evident that the amplitude of the output will decrease if the amplitude of either the pulses or the saw-tooth be decreased, and will fall to zero if either of these be reduced to zero.

The saw-tooth wave-forms are shown in Figures 2a 2b and 2c as linear, but the reasoning

is equally valid in the practical case where they are non-linear.

The receiver shown in Figure 3 is mainly similar to that shown in Figure 1, with the principal exception that a multiplicative mixing valve of the kind which may be generally described as the "hexode" type, is employed in place of the multiplicative mixing circuit of Figure 1. Such a valve has an output electrode and two input electrodes, and the output signal is the product of the two input signals. The valve actually employed is a pentagrid; this valve, as is well known, contains, in addition to the necessary electrodes of a simple hexode, a further electrode which is ordinarily employed as an oscillator anode.

In Figure 3 the pentagrid valve 4 has the signal consisting of a succession of direct voltage pulses, which is developed across resistor 24, applied to its first control grid 4a through condenser 5 by leads 5a and 5b; and has the saw-tooth voltage oscillation which is developed across resistor 36 applied to its second control grid 4d through lead 36a. Conventional self-biasing is provided by resistor 9 and condenser 10.

The output modulation frequency component of the resultant of the multiplicative mixing of the two input voltages may be obtained from either the anode 4f or from the screen grids 4b, 4c, 4e of valve 4. This component appears on these electrodes in opposite sense. In Figure 3 the component is shown as taken from the screen grids, the choice being made in view of the fact that the mean potential of the screen is lower than that of the anode. The screen current of the valve 4 develops its output potential across the resistance 19. Condenser 21 by-passes components having pulse-repetition frequency, and the output is applied through blocking condenser 11 to audio-frequency amplifier 33 and thence to loudspeaker 34.

The blocking oscillator of Fig. 3, including valve 35, operates in a manner similar to the blocking oscillator described with reference to Figure 1.

As in Figure 1, it is necessary to transmit the direct component of the output of the multiplicative mixer to the saw-tooth oscillator. The triode 35 of the blocking oscillator therefore has its grid connected through grid leak 38 and lead 38a to the screen grids of pentagrid 4, and has its cathode maintained at a substantial positive potential relative to earth by connection to a tapping on potentiometer 16 and 17, condenser 18 being provided to by-pass oscillations of pulse-repetition frequency.

The output circuit comprising resistor 36 and condenser 20 is designed to convert the pulse output of the blocking oscillator to saw-tooth waveform in the manner described with reference to resistor 36 and condenser 37 of Figure 1.

In order to increase the effectiveness of the received signal, a similar time-constant circuit is included in Figure 3 in the anode circuit of the detector valve 3, so that the direct voltage pulses

derived from the received signal are similarly converted to saw-tooth wave-form. This time-constant circuit consists of condenser 8 connected in parallel with resistor 24 in the anode circuit of detector valve 3.

I claim:

1. In a system for demodulating an input signal consisting of an angularly modulated succession of direct voltage pulses, the combination of a demodulator comprising a saw-tooth oscillation generator, a multiplicative mixer for mixing the output of said generator with said input signal and producing a modulation frequency component, output means deriving the modulation frequency component of said mixer, and means controlled by said component to produce angular modulation of the output of said generator in accordance with, but of a smaller magnitude than that of, said modulation frequency component.
2. A radio receiver for the reception of a signal consisting of a succession of pulses of radio-frequency oscillation, comprising means to convert said pulses into a similar succession of identical direct voltage pulses, a multiplicative mixer valve having two input electrodes and an output electrode, means to apply said direct voltage pulses to one of said input electrodes, a saw-tooth oscillator having a connection for supplying a saw-tooth voltage to the other of said input electrodes, a modulation frequency filter connected to said output electrode, and means responsive to the modulation frequency current from said filter for varying the frequency of said saw-tooth oscillator in accordance with, but of a smaller magnitude than that of, said modulation frequency.
3. A receiver for angularly modulated pulses comprising, in combination, a mixer to which said pulses are supplied, an oscillation generator for supplying saw-tooth waves to said mixer, said generator having a control grid, and the frequency of said saw-tooth waves being controlled by the potential applied to said grid, means for deriving from said mixer a modulation frequency component, and means for varying the potential of the grid of said oscillator in accordance with, but of a smaller magnitude than that of, said modulation frequency component.
